PENHOLDER DESK STAND

Michael Panarelli, 16 Burns Ave., Quincy, Mass. 02169

Filed June 29, 1971, Ser. No. 158,151

Term of patent 14 years

Int. Cl. D19—02

U.S. Cl. D74—5 A

FIG. 1 is a top perspective view of a penholder desk stand showing my new design;

FIG. 2 is a front perspective view; and

FIG. 3 is a rear perspective view thereof.

I claim:

The ornamental design for a penholder desk stand, substantially as shown.
